UNITED STATES PATENT OFFICE.

JOHN J. HENTZ, OF BALTIMORE, MARYLAND.

BICYCLE.

SPECIFICATION forming part of Letters Patent No. 624,651, dated May 9, 1899.

Application filed November 3, 1897. Serial No. 657,306. (No model.)

To all whom it may concern:

Be it known that I, JOHN J. HENTZ, of Baltimore city, in the State of Maryland, have invented a new and useful Improvement in 5 Bicycles, which improvement is fully set forth in the following specification and accompanying drawings.

The object of my invention is to furnish a device by which to connect or disconnect the 10 sprocket-wheels with the shaft on which they are placed, so that the motion of the shaft may be communicated to the one or the other of the sprocket-wheels, as desired, for the purpose of increasing or decreasing the speed of 15 the bicycle while propelling it on a level or up an incline.

On the figures of the drawings like letters refer to like parts.

Figure 1 is a perspective view of a bicycle 20 with my improvement applied. Fig. 2 is a view, partly in section, of the crank-shaft, sprocket-wheels, and movable couplers detached from the bicycle. Fig. 3 is a view of the inner face of a sprocket-wheel. Fig. 4 is 25 a view of the outer face of a sprocket-wheel. Fig. 5 is a perspective view of a coupler, and Fig. 6 shows the crank-shaft detached.

Referring to the figures, A is a crank-shaft of the form shown in Fig. 6, having key-seats B B. 30 C C are couplers having grooves S S, key-seats D D, keys L L, fixed in the seats, and projections E E on the faces, as illustrated in Fig. 5.

F' F' are sprocket-wheels on the axle of the 35 rear wheel, one of said wheels being of greater diameter than the other.

F F are sprocket-wheels mounted on the crank-shaft. Each wheel F has depressions G G in its face and a key-seat D' to receive a 40 key L, which latter is approximately one-half the length of the seat B in the shaft.

H is a shifter pivoted at K to the frame.

I I are arms projecting from the lower end 45 of the shifter, said arms having attached thereunto clutch-yokes J J, which engage the grooves S S in the couplings or couplers.

W is a notched bar on the frame, adapted to be engaged by the long arm P of the shifter, and M M are sprocket-chains, of usual con-

struction, for transmitting motion from the 50 crank sprocket-wheels to the sprocket-wheels on the rear-wheel shaft.

It will be observed that the crank-shaft A is supported at its middle portion only in a bearing located at the lower end of the mast 55 and that the sprocket-wheels F F and the clutch mechanisms are on the ends of the crank-shaft. The arms of the shifter carrying the yokes thus necessarily extend to the left and right of the mast, so that the forks 60 may engage the couplers on each side of the shaft-bearing.

The operation of the device is obvious. When the lever-arm P is caused to engage the notch at the left on the bar in Fig. 1, the 65 coupler C at the right-hand end of the crank-shaft is brought into engagement with the sprocket-wheel F, the key L sliding into the seat D' and the projections E E meshing with the depressions G G. The coupler at the left 70 is simultaneously thrown out of engagement with the sprocket-wheel on the left end of the pedal-shaft. The sprocket-wheels on the shaft of the rear wheel being of different diameters, the speed of the bicycle will depend 75 upon the position occupied by the shifter. It is clear that in some instances the sprocket-wheels on the shaft of the rear wheel may be of the same diameter and those on the pedal-shaft of different diameters. 80

What I claim is—

1. The combination in a bicycle-propelling mechanism, constructed and operating substantially as described, of sprocket-wheels, F' F'; sprocket-wheels, F F; shaft, A, having 85 seats, B B; couplers, C C, having projections, E E, and keys, L L; chains, M M; and a shifter; the said wheels, F F, having key-seats and depressions adapted to mesh with the keys and projections on the couplers, C C, 90 and each seat, B, being substantially twice the length of a key, L; in substance as set forth.

2. The combination in a bicycle-propelling mechanism, of a rear wheel having a shaft 95 with two sprocket-wheels thereon; a crank-shaft having two sprocket-wheels thereon; chains, M M, for transmitting motion from

the front to the rear sprocket-wheels; independent couplers, C C, having keys, L L, movable in the seats, B B, made in said shaft, long enough to always afford engagement with said keys, and adapted to also engage alternately the seats, D' D', in the sprockets, and also having grooves, S S; and a shifter,

H, provided with clutch-yokes loosely engaging the grooves, S S, in the couplers; substantially as and for the purposes set forth. 10

JOHN J. HENTZ.
